UNITED STATES PATENT OFFICE.

JULIUS H. SCHMIDT, OF BAYONNE, NEW JERSEY, ASSIGNOR OF ONE-HALF
TO PETER H. SCHIEFFLER, OF SAME PLACE.

DESIGN FOR A SUSPENSION-HOLDER FOR UMBRELLAS.

SPECIFICATION forming part of Design No. 28,877, dated June 14, 1898.

Application filed April 22, 1898. Serial No. 678,526. Term of patent 7 years.

To all whom it may concern:

Be it known that I, JULIUS H. SCHMIDT, a citizen of the United States, residing at Bayonne, in the county of Hudson and State of

5 New Jersey, have invented and produced a new and original Design for a Suspension-Holder for Umbrellas, of which the following is a specification, reference being had to the accompanying drawings, forming part thereof.

10 The leading features of the design consist of the new and original shape and configuration of the holder, substantially as shown in the accompanying drawings, in which—

15 Figure 1 is an elevation looking at one edge of the holder. Fig. 2 is a side elevation of the holder, and Fig. 3 is a view of the lower end of the holder.

20 In the drawings, A B denote the sides of the lower end of the holder, the lower ends of said sides merging into one another by means of the curved connection D.

The sides A B extend upward on inclined lines, as shown, and at their upper portions cross, though separated from, one another on the curved upwardly-inclined lines, indicated ²⁵ a b, the upper end of the side B terminating in the inwardly-turned end d. The side A at the curve a joins the upwardly-extending rod e, which terminates in the hook f.

What I claim, is—

30 The design for a suspension-holder for umbrellas, substantially as shown and set forth.

Signed at New York, in the county and State of New York, this 19th day of April, 1898.

JULIUS H. SCHMIDT.
